Philip S. McLean, ATTORNEY

UNITED STATES PATENT OFFICE.

FRED LICHTENBERG AND MICHAEL M. McCARTHY, OF YONKERS, NEW YORK.

BUILDING SLAB.

Application filed August 17, 1923. Serial No. 657,837.

To all whom it may concern:

Be it known that we, FRED LICHTENBERG and MICHAEL M. McCARTHY, citizens of the United States, and residents of Yonkers, 5 Westchester County, and State of New York, have invented certain new and useful Improvements in Building Slabs, of which the following is a specification.

Special objects of this invention are to 10 provide a reinforcement for concrete building slabs which can be readily made up from ordinary wire to suit any size of slab or block; which will impart to the slab the desired strength and durability and which 15 further, will provide an effective means of bonding adjacent slabs in a wall structure or the like.

These and other objects are attained in the embodiment of the invention illustrated 20 in the accompanying drawing, wherein:

Figure 1 is a perspective and part sectional view of a form of wall slab having features of the invention incorporated therein.

25 Figure 2 is a similar view on a smaller scale, illustrating the slabs built up into a wall structure.

Figures 3 and 4 are broken face views of two different forms of the slabs.

30 Figure 5 is a plan and part sectional view of the reinforcement or "basket" structure.

The body of the reinforcement is in the 35 nature of a helix, so that it can be wound from a single wire, in a series of loops extending continuously substantially from one end to the other of the slab. In Figure 1 the first loop 7 is closed upon itself and made fast as by means of a wire wrapping 8, and from this closed loop the wire is inclined as at 9, down to the level of the next loop, the end of which, at 10, is long enough to project beyond the edge of the finished slab. An inclined length of wire 11 extends from this projected loop back to and beyond 40 the opposite edge of the slab to form a projecting loop 12 at this edge. The winding is continued in this fashion for substantially the full length of the slab so that the slab, which is designated generally by the reference character 13, has the loops 10 and 12 45 projecting from the opposite edges thereof.

The coils of the so-called helical winding are usually flattened, as indicated, to conform generally to the cross sectional outline of the slab and the convolutions are

made so as to bring the projecting loops into staggered relation at opposite edges of the slab, as in Figures 1, 2 and 3, or directly opposite as in Figure 4.

Longitudinal reinforcements 14 are 60 shown as extending substantially the full length of the slab. These reinforcements also may be of wire, and may be interwoven over and under the inclined side wires of the helical winding, as indicated at 15. 65

If desired, the continuous helical winding may be interwoven over and under the longitudinal wires, substantially as indicated in Figure 5, the result in both cases being the two layers of reinforcing fabric 70 standing in spaced relation near the opposite faces of the slab.

To fasten the two reinforcing layers in this spaced relation, ties 16 may be provided at intervals, the same being shown in the 75 form of short tie wires, having their ends caught about the longitudinal or helical reinforcing wires at the opposite sides of the slab.

The reinforcement disclosed has the im- 80 portant advantage that it may be produced in the main by machinery, the loops being wound as a continuous coil over a mandrel, and the longitudinal wires and ties being applied either before or after removal of 85 the winding from the mandrel.

The projecting loops at the opposite edges of the slabs aid in the handling of the finished slabs, protect the slabs from injury and provide, in the finished wall, overlapping reinforcements at the bonds 17 between adjoining slabs. In building up the wall the slabs may be set so as to take advantage of the reinforcement afforded by completely overlapping the bonding loops, or where 90 the reinforcement is not so necessary, the slabs may be separated further and the overlapping be reduced to that extent, or in fact, be entirely eliminated. 95

What we claim is:

1. A concrete building slab having a flattened helical reinforcement embedded therein with loops projecting from opposite edges of the slab, longitudinal reinforcements interwoven with the coils and ties 105 connecting opposite sides of the flattened helical coils.

2. A concrete building slab having a flattened helical reinforcement embedded therein with loops of the same projecting from 110

the opposite edges of the slab and longitudinal reinforcements interwoven back and forth to opposite sides of the coils of the continuous reinforcement and embedded in the slab to brace the slab against longitudinal stress.

3. A concrete building slab having a flattened helical reinforcement embedded therein with loops of the same projecting from the opposite edges of the slab and longitudinal reinforcements interwoven with the coils of the continuous reinforcement to brace the slab against longitudinal stress and

ties engaged with the longitudinal reinforcements.

4. A concrete building slab having a flattened helical reinforcement embedded therein with the opposite sides of the coils spaced apart to lie adjacent the opposite faces of the slab and ties for holding the sides of the coils thus spaced.

In witness whereof, we have hereunto set our hands this 30th day of June, 1923.

FRED LICHENBERG.
MICHAEL M. McCARTHY.
